LG's Indoor Garden Cultivator for Veggies Goes to CES 2022, by Liu Hongzuo, on Dec. 16, 2021, model LG Tiiun, online on hardwarezone.com.*

Primary Examiner — Elizabeth A. Albert*(74) Attorney, Agent, or Firm* — Birch, Stewart, Kolasch & Birch, LLP(57) **CLAIM**

The ornamental design for a plant cultivator, as shown and described.

DESCRIPTION

FIG. 1 is a front perspective view of a plant cultivator showing our new design;

FIG. 2 is a front view thereof;

FIG. 3 is a back view thereof;

FIG. 4 is a left side view thereof;

FIG. 5 is a right side view thereof;

FIG. 6 is a top plan view thereof; and,

FIG. 7 is a bottom plan view thereof.

The broken lines depict portions of the plant cultivator that form no part of the claimed design.
